SEQUENCE AND SELECTIVE SORTABLE MARGINAL CARDS

Philip M. Zenner, New York, N. Y., assignor to
The McBee Company, Athens, Ohio, a corporation

Application September 15, 1947, Serial No. 774,144

4 Claims. (Cl. 129—16.1)

1

The present invention pertains to perforated record cards, checks, sheets, and the like (hereinafter for convenience referred to as "cards"), and more particularly to perforated cards which can be used in both sequence sorting and selective sorting.

As is well known in the art, marginally punched cards are sorted in two different ways, either by sequence sorting or selective sorting. Sequence sorting involves the rearrangement of all cards into any predetermined or desired order, while selective sorting includes the removal from a file or stack of cards of only those cards relating to a specific classification or group. Heretofore, the differences in the two card sorting procedures have required differing numbers and arrangements of holes in the cards used, rendering marginally punched cards designed for sequence sorting not adaptable to the performance of selective sorting. Conversely, cards designed, punched and notched for selective sorting have not been commercially adaptable to sequence sorting, because of the large number of holes and attendant excess card edge space per digit group which the latter procedure requires, particularly in those instances where large numbers are used to identify classifications.

It is, accordingly, an object of the present invention to provide a numeric grouping of perforations on cards adjacent their edges, which cards, when slotted or notched in a particular pattern to or between the perforations, render them capable of being readily sorted sequentially as well as selectively.

Another object of the invention is to provide a card having relatively few holes per digit group adjacent the card edge, but which, nevertheless, renders itself readily adaptable for sequence sorting and selective sorting.

A further object of the invention is to provide an improved manner of notching and slotting marginally perforated cards to enable their use selectively in sequence sorting operations or selective sorting operations.

The invention is exemplified in the following description and illustrated by way of example in the accompanying drawings, in which:

Fig. 1 is a view of a fragment of a card divided into numerical digit fields.

Fig. 2 collectively illustrates the manner in

2

which any field on the card disclosed in Fig. 1 could be notched or slotted to designate the numbers "0" to "9" inclusive.

Fig. 3 is a view of a fragment of a card illustrating its notching and slotting to designate the number "309."

Fig. 4 is a view similar to Fig. 3 illustrating the manner of designating the number "30" on the card.

10 Fig. 5 is a view of a fragment of a modified form of card embodying the invention.

In the specific form of the invention disclosed in Figs. 1 to 4, inclusive, a card 10 is provided having perforations 11, 11a adjacent one of the card edges 12 which are separated into digit fields 13 by lines 14 extending perpendicular to the card edge. Perforations or holes 11 are disposed equidistant from each other inwardly of the card edge 12 and parallel thereto. Such holes in each field 13 may be numbered "1," "2," "4" and "7" beginning adjacent the right hand line 14. Another hole 11a is provided in each field 13 inwardly of one of the other numbers, such as the numeral "1," lying on a line passing through the two holes and perpendicular to the card edge 12. This inwardly extending hole represents and is designated on the card by the number "0." Disposed in alignment with the outer row of holes 11 and adjacent a beveled corner 15 on the card is another hole or perforation 16 through which a sorting rod or needle (not shown) is to pass in connection with a selective sorting operation, as described more fully hereinafter.

35 By referring to Fig. 2, it will be noted that each of the fields 13 along an edge of the card is either slotted or notched, depending upon the particular number to be indicated in that field, which may range from "0" to "9." The number "0" is designated by an elongated slot 17 extending

40 between the "0" and "1" perforations. However, this slot does not extend to the edge 12 of the card. Other numbers are designated in a known manner by a notch 18 extending from the perforation designating a particular number on the card out to the edge 12 of the card. Thus, the numbers "1," "2," "4" and "7" are indicated by a notch 18 extending outwardly from the corresponding perforations to the edge of the card.

45 The number "3" is designated by notching both

numbers "1" and "2"; number "5" by notching both the number "4" and "1" perforations to the edge of the card; number "6" by notching the number "4" and "2" perforations to the edge of the card; number "8" by notching perforations "7" and "1" to the edge of the card; and number "9" by notching perforations "7" and "2" out to the edge of the card. In each instance, any number is either notched, or, in the event the digit in the field is to be designated as a "0," such field is slotted between the "0" and "1" numbers.

As an example, the number "309" is designated in Fig. 3, the numbers "2" and "1" perforations being notched to the edge 12 of the card, the next adjacent field being slotted between the "0" and "1" perforations, and the succeeding field being notched to the edge of the card from the number "7" and number "2" perforations. Similarly, assuming that there are a total of four fields along the edge of the card and that the number "30" is to be designated, the card would actually be both slotted and notched in the pattern of "0030," as represented in Fig. 4.

Thus, from the foregoing description, it is apparent that the digit "0" is indicated in a particular field by a slot 17 running between the "0" and "1" perforations. This mode of designating the number "0" is unlike the arrangements heretofore used, in which the number "0" is disregarded, the particular field designating "0" by remaining free from notching or slotting. In the prior arrangements, sequence sorting could be performed readily with a card of the character indicated in the drawings, but selective sorting could only be performed with great difficulty, since the selective sort was productive of a large number of selected cards which had to be visually removed from the actual cards desired. For example, in the prior arrangements the number "309," such as indicated in Fig. 3 in the drawings, would have been designated by the notched grouping in the first and third fields, but there would have been no notching or slotting in the intermediate field, thereby designating the number "0." Accordingly, attempts at selectively sorting all cards numbered "309" would have been accomplished merely by passing sorting rods and needles through the number "2" and "1" perforations in the first field and the number "7" and "2" perforations in the third field. No sorting rods or needles would have been passed through the intermediate field. Accordingly, all cards ranging from numbers "309" to "399" would have been selected by this type of sort, in view of the lack of any means for preventing cards notched in the intermediate field from dropping from the stack or pile of cards.

In the present instance, the selective sort would result in the removal of all cards which are indicative of the numbers "309."

The sorting rods or needles would be placed through the first and third fields, as before, and a sorting rod would also be placed through the "0" perforation in the center field of the stack of cards. Accordingly, upon elevation of the card stack all cards which have been both notched and slotted in accordance with the "309" designation would drop down from the remaining cards a distance equal to the distance between the "0" and "1" perforations. The remaining cards would stay in their elevated positions on the needles. Since the distance between the outer and inner rows of perforations 11, 11a is greater than the distance of the outer row of perforations 11 from the card edge 12, the cards that have

been selected, which, in the example shown in Fig. 3, have been slotted and notched to indicate the classification "309," would have dropped downwardly so their upper card edges 12 were disposed below the outer row of perforations 11 or below the sorting rod holes 16 outside of the digit fields 13 and adjacent the beveled corners 15 of the cards. Thereafter, a sorting rod or needle can be passed through the corner holes 16 in the upper cards and the other sorting needles removed, which will allow all cards which have been notched and slotted in accordance with the desired classification to drop from the remainder of the stack, which is held in suspended position on the corner sorting rod.

In the event that the number "307" were notched and slotted, instead of the number "309," all cards in which the number "7" had been notched would also drop from the stack, and such cards would include those notched and slotted to the pattern of "308" and "309," as well as "307." Thereafter, the desired cards of "307" could be visually selected from the group or set of cards that responded to the sort.

Another example of a selected classification is given in Fig. 4, in which the number "30" is notched or punched in a four digit field. If only the tens field were notched to indicate the number "30," selective sorting would be extremely difficult, since any other grouping of digits in the four fields that included the notching to the number "2" and number "1" perforations in the tens field would respond to the sort. By also slotting the "0" numbers in the digit fields that are not designated by any other number, only those cards in the stack will drop downwardly a distance equal to the distance between the inner and outer rows of perforations 11a, 11 which have been slotted in the pattern of "0030" upon passing of the sorting rods or needles through the thousands, hundreds and unit fields, as well as through the "2" and "1" perforations in the tens field.

Keypunch machines employed in connection with cards embodying the present invention are equipped to punch the "0" slot 17 in all digit fields, unless a key designating another figure is depressed. For example, in the four digit fields illustrated in Fig. 4, in which the number "30" is to be designated, if the card is placed in the machine and operated without depressing any keys whatever, the card field would be slotted in the "0" position in each of the four digit fields. If, however, the keys are first depressed to designate the number "3" in the tens field, upon operation, the machine will notch the card for the number "3" in the tens field, thereby cancelling the "0" slot in that field, and slot all other digit fields for "0," as illustrated in Fig. 4.

It is, thus, apparent that selective sorting can be performed very readily in connection with the cards whose fields have the general number groupings indicated. Cards which have been notched and slotted in the manner described herein may also be rod or needle sorted sequentially by following the usual and established procedure. In performing such sorting, the presence of ciphers in the code members is ignored, and, since the "0" designations are made on the cards with slots 17 which do not extend to the edges 12 of the cards to form notches, the presence of the "0" slots does not interfere with the sorting result in any way. As is evident to those skilled in the art, since sorting rods are not placed through the field in which the "0" slot 17

appears, in sequence sorting the presence or absence of such slot makes no difference, and the cards are sorted sequentially in the prior manner.

Fig. 5 illustrates a modified form of the invention, in which a more compact arrangement of perforations or holes in each digit field is provided. The outer row 11b of perforations in each field is indicative of the numbers "1," "2" and "4," while the inner row of perforations in each field includes a perforation 11a for the number "0" in alignment with the number "1" perforation on a line perpendicular to the card edge 12, and a second perforation 11c indicative of the number "7" on a line perpendicular to the card edge 12 and running through the center of the number "4" perforation. As is known, the numbers "7," "8" and "9" are obtained by a deep notch running from the card edge 12 to the number "7" perforation, the numbers "8" and "9" also being indicated by a shallow notch running from the card edge to the number "1" or number "2" perforations, as the case may be.

In the card illustrated in Fig. 5, the numbers "1" to "9," inclusive, are designated in each field by a shallow or a deep notch or notches 13 running from the card edge 12 to the particular perforation, or combination of perforations, while the number "0" is indicated by a slot 17 extending between the "0" and number "1" perforations, which slot does not extend to the edges 12 of the card. A stack of cards having the perforation pattern indicated in Fig. 5 are sorted in the same general fashion as was described in connection with the other cards shown in the drawings, the number "0" not being ignored, but being designated in the fields where the digit is "0" by the slot 17.

It is, accordingly, apparent that a comparatively simple card and manner of both sequence sorting and selective sorting have been provided, which enables, a grouping of numbers to be placed in each digit field adjacent the edge of the card, which is not only compactly arranged, but which numbers are relatively few, thus allowing a larger grouping of fields to be indicated along the edge of the card. The arrangement enables sequence sorting to be made rapidly in the usual manner, and also allows the same arrangement and grouping of the perforations to be used very readily in selective sorting, in which substantially only the desired cards responding to the selective sort are removed from the stack, requiring in some instances the visual removal of only a relatively small number of cards from the group or set of cards which responded to the sort.

While I have shown and described my invention specifically, it is to be understood that it is not limited to the specific examples set forth herein but is capable of modification and variation within the spirit of the invention and within the scope of the claims appended hereto.

Having thus described my invention, what I claim and desire to secure by Letters Patent is:

1. As an article of manufacture, a card having an outer row of perforations arranged adjacent and parallel to one edge of the card and an inner row of perforations adjacent and parallel to said outer row, the perforations in said inner row being aligned with perforations in said outer row in a direction perpendicular to said edge, said perforations in said rows being disposed in fields of five perforations each with a single inner perforation in each field being identified on the card by the numeral 0 and the four perforations in the outer row of each field by the

numerals 1, 2, 4, and 7, whereby the digits "1," "2," "4" and "7" of any field may each be indicated by notching the card edge to the perforation of the outer row of that field so identified and the digits "3," "5," "6," "8" and "9" may be indicated by notching the card edge to any two perforations of the outer row of that field whose combined numerical value equals that of the selected digit and whereby the digit "0" may be identified by an internal slot extending between the perforation in the inner row and a perforation in the outer row in alignment therewith.

2. As an article of manufacture, a card having formed therein similar fields of perforations relative to one edge of the card, each field of perforations comprising an outer row of four perforations arranged adjacent and parallel to the edge of the card and an inner perforation in alignment with one of said outer perforations in a direction perpendicular to said edge, the perforations of said outer row being identified on the card by the numerals 1, 2, 4, and 7, commencing with the perforation at the right hand end of each field and the inner perforation being identified on the card by the numeral 0 whereby the digits "1," "2," "4," and "7" of any field may each be indicated by notching the card edge to the perforation of the outer row of that field so identified and the digits "3," "5," "6," "8" and "9" may be indicated by notching the card edge to any two perforations of the outer row of that field whose combined numerical value equals that of the selected digit and whereby the digit "0" may be identified by an internal slot extending between the perforation in the inner row and a perforation in the outer row in alignment therewith.

3. As an article of manufacture, a card having formed therein similar fields of perforations relative to one edge of the card, each field of perforations comprising an outer row of four perforations arranged adjacent and parallel to the edge of the card and being identified on the card by the numerals 1, 2, 4, and 7, commencing with the perforation at the right hand end of the field, and an inner perforation in each field designated by the numeral 0 disposed in alignment with the perforation identified by the numeral 1 in a direction perpendicular to the card edge whereby the digits "1," "2," "4," and "7" of any field may each be indicated by notching the card edge to the perforation of the outer row of that field so identified and the digits "3," "5," "6," "8" and "9" may be indicated by notching the card edge to any two perforations of the outer row of that field whose combined numerical value equals that of the selected digit and whereby the digit "0" may be identified by an internal slot extending between the perforation in the inner row and a perforation in the outer row in alignment therewith.

4. A method of notching and slotting a marginally perforated card for subsequent sorting, said card having formed therein similar fields of perforations along one edge of the card, each field of perforations comprising an outer row of perforations arranged adjacent and parallel to said edge of the card and an inner perforation arranged in alignment with one of the outer perforations in a direction perpendicular to the adjacent card edge, said inner perforation in each field being identified on the card by the numeral 0, and the other perforations in each field being identified on the card by the numerals 1, 2,

4, and 7; which comprises notching each field in which the digits 1 to 9, inclusive, are to be indicated from the perforations designated by the numerals 1, 2, 4, or 7, or combinations thereof, to the adjacent edge of the card, and slotting the card in each field in which the digit 0 is to be indicated between the inner perforation in said field and the outer perforation in alignment therewith.
